UNITED STATES PATENT OFFICE.

FRANK J. MACDONALD, OF ELLET, OHIO, ASSIGNOR TO THE B. F. GOODRICH COMPANY,
OF NEW YORK, N. Y., A CORPORATION OF NEW YORK.

METHOD AND MACHINE FOR FORMING TABS AND APPLYING THEM TO ARTICLES.

Application filed August 25, 1924, Serial No. 733,931. Renewed August 28, 1926.

This invention relates to the art of forming tabs and applying them to articles, as in the case of the rubberized-fabric anchor tabs used in rubber overshoes to secure the 5 respective members of the buckle or fastener to the overshoe, my present invention being an improvement upon that of United States Patent No. 1,451,167, issued April 10, 1923, upon my application, and upon that of 10 United States Patent No. 1,492,646, issued May 26, 1924, upon a joint application of myself and Virgil H. Bodle.

The patents referred to describe procedure and apparatus wherein the end of a strip of 15 rubberized fabric is threaded through the eye of the buckle member, a tab-forming length of the fabric strip is severed therefrom, and the severed length is folded upon and stuck to itself in interlinked relation to the buckle 20 member.

One of the chief objects of my present invention is to provide improved procedure and apparatus whereby the work described may be more rapidly performed, as by continuously feeding the strip of tab-forming 25 material while the buckle members or the like are successively presented and receive the tab-forming lengths which are successively severed from its forward end.

Another object is to provide for increased 30 accuracy of operation, and especially to provide improved means adapted to fold the two end portions of the tab-length onto each other without substantially displacing the same with relation to the article with which 35 it is associated by the feeding of the strip.

A further object is to provide improved 40 means for feeding and guiding the tab-forming strip into association with the article, whereby misaligning effects incident to variations in the character of the strip may be avoided.

Another object is to provide improved 45 means for manipulating the buckle member or the like, whereby the latter may be rapidly handled and accurately carried into strip-receiving position and ejected from the machine after the tab has been applied thereto.

Another object is to provide an improved 50 machine adapted to operate upon buckle members of different sizes.

Another object is to provide improved means for folding the side margins of the

tab-forming strip into abutted relation at 55 the middle line of the strip notwithstanding variations in the width of the strip.

Of the accompanying drawings:

Fig. 1 is a side elevation, with portions broken away and sectioned, of a machine embodying and adapted to carry out my invention in its preferred form.

Fig. 2 is a plan view of the same.

Fig. 3 is a section on line 3—3 of Fig. 2.

Fig. 4 is a section on line 4—4 of Fig. 2. 65

Fig. 5 is a section on line 5—5 of Fig. 2, a part being shown in elevation and broken away.

Fig. 6 is an elevation of a strip-folding device, as viewed from the delivery end 70 thereof, the fabric, tab-forming strip being shown in section.

Fig. 7 is a section, on line 7—7 of Fig. 2, of strip-feeding and guiding mechanism, but at a later stage of operation than that of 75 Fig. 7.

Fig. 8 is an elevation of a buckle-member-holding wheel, a part being broken away and a part being sectioned.

Fig. 9 is a perspective view of a keeper or 80 "ladder" of a shoe buckle with a tab attached thereto, as produced by the machine.

Fig. 10 is a perspective view of finished work in the form of a tongued shoe-buckle member and a tab attached thereto. 85

General description.

Referring to the drawings, the machine comprises a base 10 which supports an intermittently driven wheel 11 adapted to receive 90 successive buckle-members, carry them to a threading position and there hold them for the threading operation, and then, by further turning, to withdraw the buckle-member transversely from the line of feed of the 95 threaded strip to cause cooperating rolls 12, 13 to fold the tab-length upon itself, the wheel being adapted to release the buckle member, so that the latter is ejected from the machine, when the tab-length has thus 100 been folded.

Also supported by the base 10 is a pair of continuously driven strip-feeding and severing rolls 14, 15, the roll 14 having mounted on its cylindrical face a severing die 16 (Fig. 105 7), which as here shown is formed integrally with the roll. Said rolls are adapted to draw the tab-forming strip, 17, of tacky,

rubberized fabric, through a folder 18, from a set of auxiliary strip-feeding rolls 19, 20, 21, and to feed the folded strip forward to thread its leading end through the eye of each successive buckle member.

Between the strip-feeding and severing rolls 14, 15 and the folding roll 12 are two pairs of auxiliary tab-feeding and guiding rolls 22, 23, 24, 25 (Fig. 7), adapted to maintain alignment of and feed forward the severed or substantially severed tab lengths. Between said tab-feeding rolls and the folding roll 12 is an adjustable tab-guiding device 26, having its tab-engaging surfaces positioned close to the tab-receiving position of the buckle-member, so that said tab-guiding device and the tab-feeding rollers are adapted to maintain accurate control and prevent buckling or misalignment of each tab as the latter passes from the severing die into the eye of the buckle member.

Strip-feeding and severing mechanism.

The strip-feeding and severing rolls 14, 15 are secured upon respective parallel shafts 27, 28, by pins 29, 30, said shafts being journaled in respective pairs of journal blocks 31, 32, 33, 34, the pairs of journal blocks being slidably mounted in respective standards 35, 36 rising from the base 10, and retained in their recesses in said standards by vertical posts 37, 38 mounted in said standards. Adjusting screws 39, 40 threaded through overhanging upper portions of the standards are provided for forcing the upper journal blocks downward to cause the rollers 14, 15 to grip the tab-forming strip, and the die 16 to sever, or substantially sever, the latter.

Between the standards 35, 36 the shafts 27, 28 are integrally formed with sets of gear teeth 41, 42, which are intermeshed, and the upper shaft, 27, at the rear of the machine, has secured thereon a gear 43 which is meshed with a gear 44, on a shaft 44^a, having a common hub with a sprocket 45, the latter being connected by a sprocket-chain 46 with a sprocket 47 secured on a shaft 48 mounted in standards 49, 50 rising from the base 10 at the strip-receiving end of the machine, said shaft 48 being adapted to be driven from a suitable source of power (not shown) through a sprocket 51 and chain 52.

The severing die 16 on the strip-feeding and severing roll 14 is preferably of V-shape, to provide a symmetrical, progressive cutting action, and is of such low height as to permit a close spacing of the rolls 14, 15 such as to cause them to grip the folded fabric strip adjacent the die and continue to feed it forward notwithstanding its severance or substantial severance by the die. To avoid excessive resistance of the fabric strip 17 to the pull of the rolls 14, 15, however, the auxiliary feed roll 19 is provided, the latter

being secured upon the shaft 48 and provided with a knurled surface, shown in Fig. 1. Said auxiliary roll is adapted to be driven at a slightly greater peripheral speed than that of the severing rolls 14, 15, the arrangement being such that it will slip with relation to the fabric strip but will engage the latter with sufficient friction, responsive to the pull of the severing rollers, to feed the fabric forward to the latter without excessive tension in the intermediate reach of the strip. The roll 20 is loosely journaled upon a stub shaft 53 mounted in the standard 49 and is adapted so to guide the fabric strip 17 as to cause the latter to have contact with the feed roll 19 throughout a large part of the latter's circumference, and the roll 21, loosely journaled upon a similar stub shaft, 54, is a guide roll for directing the strip from the source of supply (not shown) to the guide roll 53. To prevent sagging of the horizontal reach of the strip and consequent over-feeding of the strip, a bracket 55 projects from the standard 49 and is adapted slidably to support the strip.

Strip-folding mechanism.

The strip-folding device 18 comprises a block 56 formed with a strip-folding aperture and adjustably secured by a screw 56^a upon the upper end of an arm 57 which is secured at its base upon a shaft 58 rotatably mounted in the frame of the machine and urged to rotate, in a direction such as to swing the arm 57 toward the feeding and severing rolls 14, 15, by a compression spring 59 interposed between the base 10 and a rocker-arm 60 projecting from said shaft. A rocker arm 61, projecting from the other side of the shaft is provided with a set-screw 62 adapted to abut the base 10 to act against the force of the spring 59 in adjustment of the folding device from or toward the feeding and severing rolls 14, 15, to vary the character of the fold produced in the fabric strip.

The block 56, at the delivery end of its strip-folding aperture, is formed with upper and lower ear-portions 63, 64, between which are pivoted, on vertical axes, a pair of folder jaws 65, 66, formed on their adjacent faces with respective grooves, the walls of which are, in general effect, continuations of the wall of the strip-folding aperture in the block 56. Said jaws are tapered toward their delivery ends, in a manner such as to permit them to extend between the rolls 14, 15, as shown clearly in Fig. 1, so as to engage the sides of the folded strip, at its lines of fold, close to the nip of said rolls, and thus hold the strip to the proper folded form substantially to the point where it is gripped by said rolls.

For yieldingly urging the folder jaws 65, 66 toward each other, about their pivots, and

thus to cause them to maintain the folded margins of the strip in abutted, edge-to-edge relation notwithstanding variations in the width of the strip, the pivot pins 67, 68 of said jaws extend below the ear portion 64 of the block 56 and have secured on their lower ends respective inwardly extending and overlapping arms 69, 70 (see Fig. 6), a pin 71 being secured in the arm 69 and projecting into a slot 72 formed in the arm 70, the opposite end of said pin projecting from the lower side of the arm 69 and being connected by a pull spring 73 with the folder-supporting arm 57.

To prevent the margins of the fabric strip from overlapping or prematurely contacting each other, and to assure the proper angular position of the strip as it passes through the folding device, a pin 74 is mounted in the upper ear-portion 63 of the block 56 and projects downward into the passage through which the strip is drawn. For supporting and guiding the fabric strip in a flat condition at a determinate distance 25 from the folder, and so to assure smooth feeding of the strip and a determinate, uniform character of fold, an arm 75 is secured to the standard 35, and adapted to be held in different positions of adjustment, by a screw 30 76, and a pair of guide pins 77, 78 project horizontally from the lower end of said arm and are adapted to hold the fabric strip to a flat condition as it passes between them.

Buckle-manipulating devices.

Buckle holding wheels of different form are provided for the tongued members and keeper members respectively of the shoe buckles, that for the tongued members being shown in Fig. 8 and designated 84, and that for the keeper members being shown in Fig. 1 and designated 11.

The buckle holding wheel 11, or 64, is secured, by a nut 11^a and a dowel stud 11^b, upon a head 79^a formed upon a shaft 79 which is journaled in the upper end of an arm 80 which is pivoted, at its lower end, upon an eccentric shaft 81 (see Figs. 1 and 5) journaled in brackets formed on the base 10, and said shaft is adapted to be turned by a hand lever 82 to raise or lower the buckle-holding wheel 11 to adapt it for buckle members of different lengths. A set-screw 83 (Fig. 1) is threaded through one of the journal brackets of said eccentric shaft and adapted to bear upon the latter to hold it in different positions of adjustment.

The wheel 11, for the keeper members, is formed on its front side face with a plurality, here shown as three, cam-faced, keeper-holding projections or dogs 85, 85, whose outer, peripheral faces 86, 86, are concentric and flush with the outer peripheral face 87 of the wheel proper. Each of the dogs 85 is formed on its arcuate face 86 with a recess

88 adapted to receive a keeper-member 89 with the eye-portion of the latter exposed at the outer periphery of the wheel, as clearly shown in Fig. 1, and pivoted in said recess is a pawl-like latch 90 formed with a hook 91 on its outer end and adapted to be pressed against the keeper 89 to retain the latter in position during that part of the revolution of the wheel which carries the keeper to threading position and beyond 75 such position to fold the tab 92, and then to be lifted from the keeper to permit the latter, with the tab assembled therewith, to drop from the wheel. For urging the latch 90 toward its holding position, it is provided with a hinge-spring 93 (Fig. 2). For lifting it from its holding position to release the keeper 89, its journal projects from the rear face of the wheel 11 and has secured thereon a cam-arm 94 adapted to run upon a cam 95 mounted upon a boss formed on the upper end of the wheel-supporting arm and adapted to be secured in angularly adjusted positions thereon by a set-screw 96.

The wheel 84 (Fig. 8) for manipulating the tongued members, one of which is shown at 97, is substantially like the keeper-holding wheel 11, except that the dogs, designated 85^a, are formed with recesses appropriately shaped to seat the tongued members instead of the keepers, and the latches, one of which is shown at 90^a, are likewise modified, as clearly shown in Fig. 8, to act effectively upon the tongued members.

Tab-folding devices.

The tab-supporting and folding roll 12 is journaled in a bracket 98 secured to the standard 35 and is adapted to support the tab 92 close to the position at which the latter passes into the keeper 89 or tongued member 97, and said roll 12 is adapted to be run upon by the peripheral face 87 of the keeper-holding wheel 11 or the corresponding face of the wheel 84, the wheel-supporting arm 80 being connected by a pull spring 100 with the frame of the machine to hold the two yieldingly in contact, so as to assure exact positioning and movement of the buckle member and at the same time avoid 110 jamming of the work.

In order to produce the particular type of finished product here shown, in which the tab 92 is folded obliquely upon itself, the buckle manipulating assembly and the terminal tab-supporting and folding roll 12 are positioned obliquely with relation to the line of feed of the tab-forming strip 17, as shown clearly in Fig. 2, so that the tab is fed obliquely through the eye of the buckle member and consequently is folded obliquely upon itself by the subsequent coaction of said roll 12 and its mate 13.

The roll 13 is journaled upon an axle 101 projecting laterally from the upper end of 130

an arm 102 which is pivoted at its lower end upon a stud 103 projecting obliquely from a part of the machine framing, so that the roll 13 is parallel with the roll 12, and said roll 13 is constantly urged toward its mate 12 by a pull spring 104 connecting the arm 102 with the arm 57.

For withdrawing the roll 13 from the roll 12 to permit the passage of the buckle-member held by the dog 85 or 85^a of the wheel 11 or 84, the dogs are formed as cams, their faces adjacent the center of the wheel, designated 105 as to the wheel 11 and 105^a as to the wheel 84, constituting cam faces adapted to run upon the roll 13 as the dog passes between said roll and the roll 12.

Tab-feeding and guiding devices.

The lower tab-feeding rolls 22, 23 are journaled in the bracket 98 and formed with sets of gear teeth 22^a, 23^a at their front ends by which they are adapted to be driven, through an idler gear 106 mounted on the bracket 98 and meshed with a gear 107 secured on the end of the shaft 28. The upper tab-feeding rolls, 24, 25, adapted to coact with the lower rolls 22, 23, are journaled in a floating frame 108 slidably mounted on a pair of vertical guide posts 109, 109 rising from the bracket 98, and are formed at their front ends with sets of gear teeth 24^a, 25^a meshed respectively with those of the lower rolls 22, 23. Two pairs of driven rolls are thus provided which are adapted yieldingly to grip the tabs and feed them forward from the severing position to the threading position.

Secured to the top-face of the floating frame 108 by a screw 110 is a tongue-spring 111 adapted to bear yieldingly upon the tab 92 to hold the latter down against the roll 12, in alignment with the eye of the buckle member. Spring metal side guides 113, 113 are secured to the side faces of a block formed on the floating frame 108 and straddle the hold-down spring 111, their lower ends converging, with respect to the line of feed of the tab, as is clearly shown in Fig. 2, so that the leading end of each successive tab will be directed into or held in alignment with the buckle member. The side guides 113 are so formed and mounted as to stand widely apart at their work-engaging ends except as they are closed toward the work by respective nuts 114, 114 mounted upon a transverse screw 115 extending through apertures in said side guides and having its ends secured in ears formed on the floating frame 108, said side guides thus being adapted to be adjusted for tabs of different widths.

Drive mechanism for buckle-holding wheel.

The shaft 79 of the buckle-holding wheel is connected by a universal-joint device, including metal coupling disks 116, 116 and spiders 117, 117 therefor, (Fig. 2), with an

intermittently driven shaft 118 journaled in suitable brackets at the rear of the machine, the two universal joints permitting the buckle-holding wheel to be driven in its oblique position and at different positions of vertical adjustment corresponding to buckle members of different lengths.

For intermittently driving the buckle-holding wheel, to bring one after another of its dogs 85 momentarily into tab-receiving position, while another is in buckle-receiving position, a gear 119 is secured upon the shaft 118 and adapted to be driven intermittently by a mutilated gear 120 secured upon the shaft 44^a above described, and having one-third as many teeth as the gear 119.

To prevent over-running of the buckle-holding wheel, a disk 121 (Figs. 2 and 5) is secured upon the shaft 79 of said wheel and is formed on its periphery with three ratchet notches 122, 122, of appropriate form, spaced apart to correspond to the positions of the dogs 85 on the buckle-holding wheel, and a suitably formed pawl 123, adapted to be engaged in and disengaged from said notches successively, being released from one notch and engaged in the next at each revolution of the mutilated gear 120, is secured upon a rock-shaft 124 mounted in a lateral extension 125 of the arm 80 and connected by a universal coupling 126 with a shaft 127 mounted in suitable brackets at the rear of the machine and having secured thereon a rocking-lever 128 having an arm 128^a projecting into the path of an arm 129 secured upon the shaft 44^a and an arm 128^b extending in the opposite direction and connected by a pull spring 130 with the base of the machine.

Operation.

In the operation of the machine, the mechanisms described being driven through the chain 52, the rolls 14, 15 continuously rotate, drawing the fabric strip 17 through the folding device 18, pressing the folded strip to compact it and sticking its folded margins against its middle portion, and severing it, or substantially severing it, by the action of the die 16, into tab lengths 92, which are farther fed in procession over the tab-folding roll 12, by the rolls 22, 23, 24, 25, the auxiliary feed roll 19 preventing excessive tension in the fabric strip 17, and the folding device 18, in cooperation with the rolls 14, 15, folding over the side margins of the strip to its middle line.

The buckle holding wheel, being intermittently driven by the mechanism above described, stops with one of its dogs 85 in tab-receiving position and another in buckle-receiving position, as shown clearly in Fig. 1, at which time the operator inserts a buckle member, for example, one of the keepers 89, in the recess of the properly positioned dog,

the latch 90 thereof being held in raised position, as shown clearly in Fig. 1, by the cam 95. At the next partial turn of the wheel 5 the keeper is carried to threading or tab-receiving position, the latch 90 being brought against the keeper by the spring 93 when the arm 94 passes from the cam 95, so that the latch firmly holds the keeper in place.

The keeper is thus presented to receive 10 the foremost tab-length, which is obliquely threaded through the eye of the keeper by the devices described, the folding roll 13 being forced away from its mate 12 by the cam action of the dog, as will be clear upon 15 reference to Fig. 1. In the succeeding movement of the dog, from threading position, the folding roll 13, running off the cam face 105 of the dog, bears yieldingly against the tab-length, under the force of the spring 104, 20 and the tab length, in being drawn between the rolls 12, 13, is folded upon and stuck to itself in interlinked relation to the keeper, the oblique positioning of the keeper-manipulating and tab-folding devices resulting 25 in an oblique line of fold and an oblique disposition of the two halves of the tab, as shown in Figs. 9 and 10.

The hook 91 on the end of the latch 90 serves to engage the keeper securely as the 30 latter is drawn from the rolls 12, 13, to assure the withdrawal of the keeper although it may be partially dislodged from its seat by engagement of the roll 12 with its projecting rear portion, and the latches 90^a and the 35 seating recesses of the wheel 84 are so formed, as shown clearly in Fig. 8, as securely to hold the tongued-member 97, similarly to assure its withdrawal.

At the end of the tab-folding movement of 40 each dog, the latch 90, in the case of the wheel 11, or the latch 90^a in the case of the wheel 84, is withdrawn from the buckle member by the action of the cam 95, permitting the finished buckle member assembly, now at the lower part of the wheel's 45 orbit to fall from the machine into a receptacle (not shown).

The ratios of the gearing as shown are such that the movement of each dog from buckle-receiving to tab-receiving position takes place in about one-third of the time required for the feeding of each tab-length, so that each tab-length is quickly withdrawn from the line of feed, leaving the tab-receiving position vacant, as to the tab-lengths, until after the next buckle member has been brought into position to be threaded. This permits the strip-feeding mechanism to be continuously driven, so that its 50 drive mechanism may be of simple construction, and variations of tension and non-uniformity of operation upon the fabric strip are avoided. The feed of the strip, being continuous, does not require to be so 55 rapid, for a given production, as the inter-

mittent feed of the machines described in the patents above referred to, and a steadier, better controlled manipulation of the fabric strip is thus provided.

The improved tab-folding mechanism 70 above described has the advantage, over the machines of the above mentioned patents, that the roll 13, being relatively small, being loosely journaled, and having an abrupt initial relative movement transverse to the threaded tab, folds the tab sharply, immediately at the eye of the buckle member, and with substantially no effect of moving the tab lengthwise, in the eye of the buckle member, as distinguished from a large, driven 80 roll initially having the tab in tangent relation thereto.

The folding device 18 or the guides 77, 78 may be adjusted from and toward the rolls 14, 15 to vary the character of the fold or 85 to accommodate strips of different widths, but in practice I find that with a proper setting of the device the yieldingly held folding jaws 66, 66, in conjunction with their associated elements, provide an accurately 90 pleated strip, with the edges of the fabric abutted at its middle line, although the width of strip used be varied throughout a considerable range.

Vertical adjustment of the buckle holding 95 wheel by means of the hand lever 82 and setscrew 83 as described, in conjunction with the present type of tab-folding device, permits operation upon buckles of different sizes without substitution of the buckle-holding 100 wheel.

The tab-feeding means positioned at the delivery side of the severing position results in improved operation, as such feeding means prevents any uneven driving force of 105 the severing die or rolls from swinging the forward end of the tab-length out of alignment, and also prevents misaligning of the tab-length by the folding movement of the one preceding it.

My invention is susceptible of various modifications within its scope, and I do not wholly limit my claims to the exact procedure described or the specific construction 110 shown.

I claim:

1. The method of making tabs and applying them to articles which comprises continuously feeding a strip of tab-forming material and severing it into successive tab-lengths as it passes a severing station, presenting successive articles in position to receive the successive tab-lengths, and folding each tab length about a part of the article.

2. The method of making tabs and applying them to articles which comprises feeding a strip of tab-forming material and severing it into successive tab-lengths as it passes a severing station, feeding said tab-lengths by engagement therewith at a more advanced 125

position on the delivery side of the severing station, and presenting successive articles in position to receive the successive tab-lengths.

3. The method of making tabs and applying them to articles which comprises continuously feeding a strip of tab-forming material and severing it into successive tab-lengths as it passes a severing station, feeding said tab-lengths by engagement therewith at a more advanced position on the delivery side of the severing station, and presenting successive articles in position to receive the successive tab-lengths.

4. The method of making tabs and applying them to articles which comprises continuously feeding a strip of tab-forming material and severing it into successive tab-lengths as it passes a severing station, presenting successive articles in position to receive the successive tab-lengths, and moving said articles aside, in succession, from the line of feed of the strip, to withdraw the tab-lengths successively from the tab-receiving position.

5. The method of making tabs and applying them to articles which comprises feeding a strip of tab-forming material and severing it into successive tab-lengths as it passes a severing station, feeding said tab-lengths by engagement therewith at a more advanced position on the delivery side of the severing station, presenting successive articles in position to receive the successive tab-lengths, and moving said articles aside, in succession, from the line of feed of the strip, to withdraw the tab-lengths successively from the tab-receiving position.

6. The method of making tabs and applying them to articles which comprises continuously feeding a strip of tab-forming material and severing it into successive tab-lengths as it passes a severing station, feeding said tab-lengths by engagement therewith at a more advanced position on the delivery side of the severing station, presenting successive articles in position to receive the successive tab-lengths, and moving said articles aside, in succession, from the line of feed of the strip, to withdraw the tab-lengths successively from the tab-receiving position.

7. The method of making tabs and applying them to apertured articles which comprises continuously feeding a strip of adhesive tab-forming material and severing it into tab-lengths as it passes a severing station, presenting the apertured articles successively in position to receive the successive tab-lengths through their apertures, and folding each tab-length and sticking it to itself in interlinked relation to the article.

8. Tab-applying apparatus comprising means for continuously feeding a strip of tab-forming material and severing it into successive tab-lengths as it passes a severing station, means for presenting successive articles in position to receive the successive

tab-lengths, and means for folding each tab-length about a part of the article.

9. Tab-applying apparatus comprising means for feeding a strip of tab-forming material and severing it into successive tab-lengths as it passes a severing station, means for feeding said tab-lengths by engagement therewith at a more advanced position on the delivery side of the severing station, and means for presenting successive articles in position to receive the successive tab-lengths.

10. Tab-applying apparatus comprising means for continuously feeding a strip of tab-forming material and severing it into successive tab-lengths as it passes a severing station, means for feeding said tab-lengths by engagement therewith at a more advanced position on the delivery side of the severing station, and means for presenting successive articles in position to receive the successive tab-lengths.

11. Tab-applying apparatus comprising means for continuously feeding a strip of tab-forming material and severing it into successive tab-lengths as it passes a severing station, and means for presenting successive articles in position to receive the successive tab-lengths and for moving said articles aside, in succession, from the line of feed of the strip, to withdraw the tab-lengths successively from the tab-receiving position.

12. Tab-applying apparatus comprising means for feeding a strip of tab-forming material and severing it into successive tab-lengths as it passes a severing station, means for feeding said tab-lengths by engagement therewith at a more advanced position on the delivery side of the severing station, and means for presenting successive articles in position to receive the successive tab-lengths, and for moving said articles aside, in succession, from the line of feed of the strip, to withdraw the tab-lengths successively from the tab-receiving position.

13. Tab-applying apparatus comprising means for continuously feeding a strip of tab-forming material and severing it into successive tab-lengths as it passes a severing station, means for feeding said tab-lengths by engagement therewith at a more advanced position on the delivery side of the severing station, and means for presenting successive articles in position to receive the successive tab-lengths, and for moving said articles aside, in succession, from the line of feed of the strip, to withdraw the tab-lengths successively from the tab-receiving position.

14. Tab-applying apparatus comprising means for continuously feeding a strip of tab-forming material and severing it into successive tab-lengths as it passes a severing station, means for presenting successive articles in position to receive the successive

tab-lengths and for moving said articles aside, in succession, from the line of feed of the strip, to withdraw the tab-lengths successively from the tab-receiving position, 5 and means for folding the tab-length about a part of the article as the latter is so moved.

15. Tab-applying apparatus comprising means for feeding a strip of tab-forming material and severing it into successive tab-lengths as it passes a severing station, means 10 for feeding said tab-lengths by engagement therewith at a more advanced position on the delivery side of the severing station, means for presenting successive articles in position to receive the successive tab-lengths, and for moving said articles aside, in succession, from the line of feed of the strip, to withdraw the tab-lengths successively from the tab-receiving position, and means 15 for folding the tab-length about a part of the article as the latter is so moved.

16. Tab-applying apparatus comprising means for continuously feeding a strip of tab-forming material and severing it into successive tab-lengths as it passes a severing station, means 25 for feeding said tab-lengths by engagement therewith at a more advanced position on the delivery side of the severing station, means for presenting successive articles in position to receive the successive tab-lengths, and for moving said articles aside, in succession, from the line of feed of the strip, to withdraw the tabs successively from the tab-receiving position, 30 and means for folding the tab-length about a part of the article as the latter is so moved.

17. Tab-applying apparatus comprising a pair of presser members, an orbital article-carrying member whose orbit passes between 40 said presser members, and means for associating a length of tab-forming material with an article carried by said article-carrying member.

18. Tab-applying apparatus comprising a pair of presser members, an orbital article-carrying member whose orbit passes between 45 said presser members, means for driving said article-carrying member and stopping it in an article-receiving position and in a tab-receiving position alternately, and means for associating a length of tab-forming material with an article carried by said article-carrying member.

19. Tab-applying apparatus comprising a pair of presser members, an orbital article-carrier whose orbit passes between said 50 presser members, and means on said carrier adapted to clamp an article thereon as said carrier passes to said presser members and to release said article as said carrier passes from said presser members.

20. Tab-applying apparatus comprising a pair of presser members, an orbital carrier for an article to be associated with a tab, the

orbit of said carrier passing between said 65 presser members, means for folding a tab-length associated with an article on said carrier about a part of the article, clamping means on said carrier for holding the article thereon, and a cam, in the orbit of said 70 clamping means, adapted to effect a closing of said clamping means at one part of its orbit and an opening thereof at another part.

21. Tab-applying apparatus comprising a pair of presser members, means yieldingly 75 urging them together, and an orbital article carrier whose orbit passes between said presser members, said carrier being formed as a cam for forcing said rollers apart for the passage of the article. 80

22. Tab-applying apparatus comprising a pair of presser members, means yieldingly urging said presser members toward each other, a wheel, an article-holding member mounted on said wheel and adapted to pass 85 between said presser members as said wheel is turned, and cam-means on said wheel for forcing said presser members apart to permit the passage of said article-holding member.

23. Tab-applying apparatus comprising a 90 wheel, an article carrier projecting from an end face of said wheel, a presser member mounted in the plane of rotation of said article carrier, yielding means urging said presser member, in said plane, toward the 95 path of said article carrier, and means acting against the force of said yielding means for retracting said presser member to permit the passage of said article carrier.

24. Tab-applying apparatus comprising a 100 pair of presser members, an orbital article-carrier whose orbit passes between said presser members, and means for separating said presser members to permit the passage of said carrier and for closing them together 105 upon a tab associated with an article on said carrier.

25. Tab-applying apparatus comprising a 110 pair of presser members, an orbital article carrier, and spaced apart article-holding devices on said carrier alternating with open spaces in the line of the carrier's orbit, said article-holding devices being adapted to pass successively between said presser members as the carrier is driven. 115

26. Tab-applying apparatus comprising means for feeding a strip of tab-forming material, means for presenting an article in position to receive said strip as it is so fed, and means for supporting the article-presenting means in different positions to adapt it for articles of different dimensions. 120

27. Tab-applying apparatus comprising means for feeding a strip of tab-forming material, orbital means for presenting successive articles in position to receive a strip so fed, means for securing the article-presenting means in different positions to adapt 125

it for articles of different dimensions, and means adapted to drive said article-presenting means in such different positions.

28. Tab-applying apparatus comprising means for continuously feeding a procession of tab-lengths of strip material, orbital means for presenting successive articles in position to receive the successive tab-lengths and move them transversely from the line of feed, and means for driving the article-presenting means in such timed relation to the tab-feeding means as to remove each article and its tab from tab-receiving position and present the succeeding article thereat before the arrival of the succeeding tab-length.

29. Tab-applying apparatus comprising means for presenting successive articles at a tab-receiving position and means cooperating therewith to fold successive tab-lengths associated with the successive articles, said article-presenting means comprising an intermittently driven orbital member having a succession of article holding devices thereon, and having stopping positions such as to hold one of said article holding devices in tab-receiving position while another is in article-receiving position.

30. Tab-making apparatus comprising means for feeding a strip of tab-forming material, means for folding over the lateral margins of the strip as it is so fed, the folding means comprising a pair of pivoted folder jaws, and means for severing the folded strip into successive tab-lengths.

31. Tab-making apparatus comprising means for feeding a strip of tab-forming material and severing it into successive tab-lengths, and means for folding over the lateral margins of the strip as it passes to the first said means, the folding means comprising a pair of folder jaws pivoted on axes substantially perpendicular to the plane of the middle portion of the strip, said jaws extending from their pivots toward the delivery side of the folding device, and means for yieldingly urging said jaws toward each other.

32. Tab-applying apparatus comprising means for supporting an apertured article in position to receive through its aperture a strip of tab-forming material, means for propelling said strip through said aperture, and non-rotary strip-guiding means having guiding surfaces converging toward and extending substantially to the aperture of said article in its tab-receiving position.

33. Tab-applying apparatus comprising strip-feeding and supporting means including a terminal supporting member, means for presenting an article in close-up position immediately to receive a strip as the latter is projected past said terminal supporting member, and hold-down means, at substantially the same position in the path of the strip as that of the terminal support-

ing member, for holding the strip against said terminal-supporting member as the strip is so projected.

34. Tab-applying apparatus comprising strip-feeding and supporting means including a terminal supporting roller, means for presenting an article in close-up position immediately to receive a strip as the latter is projected past said roller, and non-rotary strip-guiding means directly over said roller.

35. Tab-applying apparatus comprising strip-feeding and supporting means including a strip-supporting member, means for supporting an article to receive the strip and non-rotary strip-guiding means positioned over said supporting member and comprising a hold-down member and a pair of side-guide members, the guiding faces of the three converging toward the delivery side of the device.

36. Tab-applying apparatus comprising means for feeding a strip of tab-forming material, means for presenting an article in position to receive the strip as it is so fed, and guiding means for said strip comprising a tongue spring adapted to bear upon a broad face of the strip and a pair of spring members adapted to act as side-guides for the strip.

37. Tab-applying apparatus comprising means for feeding a strip of tab-forming material, means for presenting an article in position to receive the strip as it is so fed, a pair of spring members adapted to act as side-guides for the strip, and means for springing said members from and toward each other to adapt them for strips of different widths.

38. Tab-applying apparatus comprising means for feeding a strip of tab-forming material and severing it into successive tab-lengths, tab-feeding means adapted to feed the tab-lengths forward from the severing means, and means for presenting successive articles to receive the successive tab-lengths, said tab-feeding means comprising a tab-supporting roll and a presser-roll mating therewith and so mounted that it may be freely lifted therefrom, said rolls being geared together when in operative position.

39. Tab-applying apparatus comprising means for feeding a strip of tab-forming material and severing it into successive tab-lengths, tab-feeding means adapted to feed the tab-lengths forward from the severing means, and means for presenting successive articles to receive the successive tab-lengths, said tab-feeding means comprising a pair of tab-supporting rolls, a movable bearing thereover, means for vertically guiding said bearing, a pair of presser-rolls journaled in said bearing and adapted to mate with said tab-supporting rolls respectively, and gears on said tab-supporting rolls and said presser rolls adapted to mesh and unmesh as said

bearing is lowered into operative position and lifted therefrom.

40. Tab-applying apparatus comprising strip-feeding and supporting means including a terminal strip-supporting roll, an article holding wheel formed with an annular peripheral face, means for yieldingly holding said wheel so that said face runs upon said roll, a plurality of article-holding devices projecting from an end face of said wheel and spaced apart circumferen-

tially of the wheel, and a presser roll so mounted that it may be brought into mating relation to said terminal strip-supporting roll between said article-holding devices ¹⁵ and moved away from said terminal strip-supporting roll to permit the passage of said devices.

In witness whereof I have hereunto set my hand this 19th day of August, 1924.

FRANK J. MACDONALD.
